VENDING MACHINE

Julius King, New York, N. Y.

Application August 19, 1941, Serial No. 407,490

4 Claims. (Cl. 312—64)

This invention relates to a match book vending machine wherein a rotatable magazine comprising a plurality of columns of stacked articles is periodically given a partial rotation, the vending machine comprising means for ejecting a plurality of the said match books or like articles from successive columns in the said magazine, whereby the columns are in an equally depleted state at all times.

An object of this invention is to place all the actuating mechanism below the magazine so as to permit utilization of the entire outer circumferential area of the magazine and to increase the capacity of the machine.

Another object of this invention is to provide columns having U-shaped lower extensions for supporting the stacked articles, while providing transverse passages through the said U-shaped extensions through which a plurality of the stacked articles are ejected from successive columns upon a chute.

Another object of this invention is to provide metal weights having a height greater than the height of the transverse ejecting passages so that when the magazine is empty, any attempt to actuate the ejector arm will only cause the weight to be forced against the rear wall of a column and prevent complete inward movement of the coin-controlled slide and thus preventing the loss of coins into a coin collection box when the vending machine is empty.

Another object of this invention is to provide an adjustable ejector whereby the height of the ejector may be changed to correspond to the height of the number of articles to be ejected, and so that the machine disclosed herein may be set to eject one or more articles of the desired thickness for a single coin.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a cross-sectional view of the vending machine, the section being taken as on line 1—1 in Figure 2 and showing an integral top cover plate and door broken away.

Figure 2 is a top view, with the top cover plate and door removed.

Figure 3 is a cross-sectional view, the section

being taken as on line 3—3 in Figure 1, showing the actuating mechanism below the magazine, the columns being omitted.

Figure 4 is a top plan view of a latch bolt on an enlarged scale.

Figure 5 is an end view of a tiltable pawl and a coin-controlled slide plate on an enlarged scale.

Figure 6 is a side view of a vertically adjustable ejector.

10 In the illustrated embodiment of the invention, the numeral 10 indicates a vending machine particularly designed for dispensing match books. The machine comprises a casing 11 having centrally disposed therein a hollow vertical shaft 12, the lower end of which is supported on a plate 13 fixed to the bottom 14 of the casing 11. The upper end of the shaft 12 is releasably retained by engagement with a pivot 15 in the cover plate 16 which is removably positioned 20 over the top of the casing 11.

Secured to the shaft 12, such as by means of a spider 17 is a magazine 18 having a plurality of closely positioned vertical columns 19 of rectangular cross-section and arranged in side by side relation around the circumference of the magazine. Each of the columns 19 has its outer side at the periphery of the magazine, vertically slotted at 20 for convenience in filling the magazine.

30 Each of the columns 19 has a substantially U-shaped extension 21 at its lower end, the extension being narrower than the radial dimension of a column and being positioned adjacent the inner wall 22 of the column.

The extension 21 forms a bottom wall for the column so that the match books to be dispensed may be supported therein and stacked to the top of the column.

The adjacent columns 19 are connected and 40 firmly held together by means of tubes 23 extending from disks 24 which are fixed to the shaft 12 at points substantially intermediate the ends thereof and form upper and lower spiders 17.

An arm 25 is pivotally mounted on a stud 26 45 threaded in a horizontal bracket 27 which is fixed to the casing 11. The bracket 27 has an integral vertically extended lug 28 serving as a stop which limits the swinging movements of the arm 25 in the direction of the shaft 12.

50 The free end of the arm 25 carries an ejector 30 of rectangular form and of a height to permit swinging motion through one of the transverse passages 31 formed above one of the U-shaped extensions 21, best shown in Figure 1.

A coil spring 32 has one end secured to the arm

25 and the other secured to the bracket 27 and urges the arm 25 and the ejector 30 away from one of the columns and out of the rotary path of the magazine 18.

An inclined chute 35 is secured in the casing 11 below the magazine 18 and passes through a discharge opening (not shown) at one side of the front wall 37 of the casing. The chute 35 is positioned in alignment with a transverse discharge passage at the bottom of at least one of the columns 19.

A notched or toothed wheel 40 is secured to the shaft 12, slightly above the bottom plate 13. The notches 41 are circumferentially spaced to provide a number of notches equal to the number of columns. The notches are substantially V-shaped and are positioned in radial directions on the wheel 40. A spring-pressed latch bolt 42 having a V-shaped end 43 is slidably mounted in a radial direction so as to enter into resilient engagement with a notch 41, the notched wheel 40 being adjusted on the shaft 12 so as to retain the magazine 18 with one of the columns 19 normally in alignment with the chute 35 and with its transverse opening 31 in alignment with the ejector 30. The magazine may thus be given partial rotations to bring successive columns into alignment with the ejector, the latch bolt 42 riding on the outer periphery of the wheel 40 and enters successive notches 41.

As best shown in Figure 4, on an enlarged scale, the latch bolt 42 has through slots 44 at its end portions. The slots provide passage therethrough for pins 45 which are secured in the bottom of the casing. A coil spring 46 is fastened at one end to one of the pins 45 and at the other end to a pin 47 fixed to the upper surface of the latch bolt 42 and serves to press the V-shaped end 43 of the latch bolt into resilient engagement with the notched wheel 40.

A ratchet wheel 50 is secured to the shaft 12 in spaced relation above the notched wheel 40. The ratchet wheel 50 has teeth 51 equal in number to the number of columns 19. Each tooth 51 has a radially positioned side and an inclined side, as best shown in Figure 3.

A coin-controlled mechanism 55 is secured in any suitable manner to the casing 11. The mechanism 55 comprises a slide 56 having a coin-receiving aperture 57. Secured to the slide 56 is a resiliently mounted pawl 58 which, as best shown in Figure 5, is adapted to swing sideways away from the ratchet teeth when moved inwardly and clears two of said teeth. When the said slide is withdrawn, the tiltable pawl engages the ratchet teeth 51 and rotates the magazine a distance corresponding to the distance between two successive columns.

The pawl 58 is pivotally mounted on a pin 59 in a bracket 60 fixed to the slide 56. A spring 61 fixed to the bracket 60 presses against a side wall of the pawl and forces it against a fixed upright wall 62 of the bracket 60. The pawl is thus adapted to swing away from the wall 62 and away from the ratchet teeth 51 against the tension of the spring 61. The upper portion of the pawl is of triangular form, with the apex of the triangle facing the teeth 51.

The slide 56 has an upwardly extending post 65 which is positioned to contact an outer wall 66 of the ejector 30 on its inward movement and swings the ejector a distance sufficient for removing a number of match books from the lower end of the column 19. A spring 67 interposed between the inner end of the slide 56 and a wall

of the casing 11 serves as a means for automatically returning the said slide to its normal position, as best shown in Figure 1.

As shown in Figure 1 the match books 70 which are made of substantially triangular form are stacked successively with a small sized end superimposed over a large sized end so as to have the top match book substantially level. Each column has an individual metal weight 71 which facilitates the downward movement of the stacked match books as they are withdrawn at the bottom of the stack. It is to be noted that the height of the weights 71 is greater than the height of the ejecting passage 31 at the bottom of a column and that the weights in lowermost positions form a bar to the passage of the ejector through the transverse passages and prevent the complete inward movement of the slide member when the dispensing machine is empty. This arrangement prevents the loss of a coin to the consumer in the event the columns of the magazine are empty.

It is to be noted that the cover plate 16 has an integral side wall 16' which when removed from the casing provides access from the top and from the side of the columns as they face the open side of the casing.

As shown in Figure 6, I have provided a modified ejector 30' which may be adjusted in a vertical direction so that its height may be changed to correspond to the height of the number of articles to be ejected from the successive columns. For this purpose, the ejector 30' is made of two relatively slidable members 72, 73. The arm 25 has an angular end wall 74 and a screw 75 threaded therein. The ejector member 72 has a lower slot 76 through which the screw 75 passes and by which the member 72 may be adjusted vertically in relation to the arm 25. The member 72 also has an upper slot 77 through which passes a screw 78 threaded into the ejector member 73 and by means of which the member 73 may also be adjusted vertically. It is thus possible to adjust both ejector members 72, 73 in vertical directions so as to make the overall height of the ejector 30' to correspond to the height of the number of articles it is desired to be ejected in a single operation.

It is to be noted that while I have shown the transverse passages 31 as corresponding to the combined height of two match books when placed with the small end superimposed over a large sized end, that I may make the height of the said passage to correspond to the maximum total height of four match books, etc. as desired and to adjust the ejector 30' to eject a larger number of match books.

It is to be noted that the upper surface of the ejector is a flat level plane and that this level surface acts as a substantially fixed support for the remainder of the match books above those being ejected until the ejection is complete, when the outward swing of the ejector will permit the remaining match books to drop to the bottom or supporting surface of the column.

The coin-controlled mechanism 55 is well known in the art and may be in the form shown in Patent No. 2,031,160.

In accordance with the patent statutes I have described and illustrated the preferred embodiment of my invention, but it will be understood that various changes and modifications can be made therein without departing from the spirit of the invention as defined by the appended claims.

I claim:

1. In a plural column mechanism for dispensing match books and like articles and for maintaining all of said columns in an equally depleted state, a casing having a horizontal base, an inclined chute above said base, said casing having a discharge opening at the lower end of one of its walls and in alignment with said chute, a magazine rotatably supported by an axle mounted on said base, said magazine having a plurality of columns each arranged to support a stack of articles in upright position to be dispensed, each of said columns having a U-shaped extension for supporting said stacked articles and providing a transverse passage at its lower end, an arm pivotally mounted to swing horizontally below said magazine and having an ejector positioned for movement through one of said respective transverse passages for removing a plurality of said stacked articles from a column in said magazine, a spring urging said arm away from said column, latch means in operative engagement with said axle for retaining said magazine with one of said columns normally in alignment with said chute and with its transverse opening in alignment with said ejector, a ratchet wheel on said axle, a slide member having a tiltable resilient detent adapted to move away from one of said ratchet wheel teeth on its inward movement and to engage a ratchet tooth and rotate said ratchet wheel and said magazine on its outward movement for moving said stacked columns successively into alignment with said chute, said slide member having an upwardly extending post adapted to swing said ejector into article removing position, and a spring secured to said slide member for returning said slide member to its normal operating position outside said casing and for automatically rotating said magazine during said return movement to bring another of said columns into article ejecting position.

2. In a plural column mechanism for dispensing match books and like articles and for maintaining all of said columns in an equally depleted state, a casing having a base, an inclined chute above said base, said casing having a discharge opening at the lower end of one of its walls and in alignment with said chute, a magazine rotatably supported by an axle mounted upright on said base, said magazine having a plurality of columns each arranged to support a stack of articles in upright position to be dispensed, each of said columns having a U-shaped extension at its lower end for supporting said stacked articles and providing a transverse passage at said lower end, said extension forming a bottom wall for said column and being of less width than the radial extent of said column, an arm pivotally mounted to swing horizontally below said magazine and having an ejector positioned for movement through one of said respective transverse passages for removing a plurality of stacked articles from a column in said magazine, a spring urging said arm away from said column, latch means in operative engagement with said axle for retaining said magazine with one of said columns normally in alignment with said chute and with its transverse opening in alignment with said ejector, a ratchet wheel on said axle, a slide member having a tiltable resilient detent adapted to move away from one of said ratchet wheel teeth on its inward movement and to engage a ratchet tooth and rotate said ratchet wheel and said magazine on its outward movement for moving one of said stacked columns into alignment with said chute, said slide member having an upwardly extending post adapted on the inward movement of said slide member to swing said ejector into article removing position, and means for automatically returning said slide member to its normal operating position outside said casing and for automatically rotating said magazine during said return movement to bring another of said columns into article ejecting position.

3. In a plural column mechanism for dispensing match books and like articles and for maintaining all of said columns in an equally depleted state, a casing having a base, an inclined chute above said base, said casing having a discharge opening at the lower end of one of its walls and in alignment with said chute, a magazine rotatably supported by an axle mounted upright on said base, said magazine having a plurality of columns each arranged to support a stack of articles in upright position to be dispensed, each of said columns having a U-shaped extension at its lower end for supporting said stacked articles and providing a transverse passage at said lower end, said extension forming a bottom wall for said column and being of less width than the radial extent of said column, an arm pivotally mounted to swing horizontally below said magazine and having an ejector positioned for movement through one of said respective transverse passages for removing a plurality of stacked articles from a column in said magazine, a spring urging said arm and ejector away from said column, spring-pressed latch means in operative engagement with a toothed wheel on said axle for retaining said magazine with one of said columns normally in alignment with said chute and with its transverse opening in alignment with said ejector, a ratchet wheel secured to said axle above said toothed wheel, a slide member having operatively connected thereto a tiltable resilient detent adapted to move away from said ratchet wheel teeth on its inward movement and to engage a ratchet tooth and rotate said ratchet wheel and said magazine on its outward movement for moving one of said stacked columns into alignment with said chute, said slide member having an upwardly extending post adapted on the inward movement of said slide member to swing said ejector into article removing position, and means for automatically returning said slide member to its normal operating position outside said casing and for automatically rotating said magazine during said return movement to bring another of said columns into article ejecting position.

4. In a plural column mechanism of the coin controlled type for dispensing match books and like articles and for maintaining all of said columns in an equally depleted state, a casing having a base and an inclined chute, a magazine rotatably supported by an axle mounted upright on said base, said magazine having a plurality of columns each arranged to support a stack of articles in upright position to be dispensed, each of said columns having a U-shaped extension at its lower end for supporting said stacked articles and providing a transverse passage at said lower end, said extension forming a bottom wall for said column and being of less width than the radial extent of said column, an arm pivotally mounted to swing horizontally below said magazine and having an ejector positioned for movement through one of said respective transverse passages for removing a plurality of stacked bookform articles

from a column in said magazine to said chute, a spring urging said arm and ejector away from said column, spring-pressed latch means in operative engagement with a toothed wheel on said axle for retaining said magazine with one of said columns normally in alinement with said ejector, a ratchet wheel secured to said axle above said toothed wheel, a slide member having operatively connected thereto a resilient detent adapted to move away from said ratchet wheel on its inward movement and to engage a ratchet tooth and rotate said ratchet and said magazine on its outward movement for moving one of said stacked columns into alinement with said chute, said slide member having a post adapted on the inward movement of said slide member to cause actuation of said ejector into article removing posi-

tion, and means for automatically returning said slide member to its normal operating position outside said casing and for automatically rotating said magazine during said return movement
5 to bring another of said columns into article ejecting position, each of said columns having a weight vertically slidable therein, the height of each of said weights being greater than the height of the ejecting passage at the lower end
10 of said column, said weights in the lowermost positions forming a bar to the passage of said ejector through said transverse passages and preventing the complete inward movement of said slide member when said dispensing machine is
15 empty.

JULIUS KING.
